UNITED STATES PATENT OFFICE.

OTTO C. F. MEISEL, OF BOSTON, MASSACHUSETTS, ASSIGNOR TO MEISEL PRESS MANUFACTURING COMPANY, OF BOSTON, MASSACHUSETTS, A CORPORATION OF MASSACHUSETTS.

PRINTING PRESS.

Application filed May 6, 1924. Serial No. 711,365.

The present invention relates to printing mechanism by the use of which two jobs of printing may be carried on simultaneously by a single mechanism and, in another aspect, whereby single mechanism may be utilized either to produce relatively elaborate work or, without diminution in output, to produce simultaneously several kinds of simpler work. Thus, in the example which I have chosen for description here for purposes of illustration four color printing may be carried on or an equal number of sheets of two color work may be produced in the same time and these may be two different jobs which are produced simultaneously.

My invention may be illustrated by its application to a multi-couple press of the ring gear type such as that described in detail in the patent to C. A. Meisel, 1,399,360, dated Dec. 6, 1921, to which patent I refer for a description of details not illustrated in the accompanying drawings.

This particular embodiment of my invention may be clearly understood by reference to the following description taken in connection with the drawings, wherein:

Fig. 1 is a diagrammatic longitudinal section through the press;

Figs. 2 and 3 are sections on the lines 2—2 and 3—3 of Figs. 1 respectively;

Figs. 4^a and 4^b are elevations of the cam means, the nearer portion of the cam shown in Fig. 4^b being shown as removed laterally from the further portion shown in Fig. 4^a; and

Figs. 5^a and 5^b are similar views of change cams utilized when the press is used for printing two two-color jobs.

Referring to Fig. 1 of the drawings, I have there illustrated a multi-couple four color press substantially similar to that disclosed in the Meisel patent above referred to and embodying a sheet carrier comprising a pair of ring gears 7 connected by the gripper bars 9, 11 and 13. The structure has somewhat the appearance of a lantern wheel and the whole is rotated on the supporting rolls 15 so that sheets delivered to the gripper bars by the feeding in cylinder 17 and transfer cylinder 19 are carried through a cylindrical path over the supporting segments 21 and through the printing couples I, II, III and IV arranged about the cylindrical path and comprising the form cylinders

23 and the cooperating impression cylinders 25. Suitable throw-off means are provided for moving the impression cylinders inwardly away from the sheet path and out of cooperation with the form cylinders which it will be unnecessary to describe in detail as they may be like the throw-off means described in the patent referred to. It will be sufficient here to say that a throw-off is effected through the reciprocation of the radially extending arms 27 I, 27 II, 27 III and 27 IV, corresponding to the several couples and controlled by suitable rotary cam mechanism carried by the central shaft 29 at the center of rotation of the ring gears.

In the operation of such a press as described in the patent referred to, a succession of sheets is carried through the several couples and each couple in succession prints on every sheet in a different color, thus producing four color work. My invention contemplates utilizing the press in this manner for producing four color work but when desired by simple adjustments causing each couple to print only on certain of the sheets which are passing through the press, these sheets being those which appear at regular intervals in the series as, for example, every second sheet. Thus, for example, couples I and III may print on certain of the sheets and couples II and IV on the other sheets. The press may be run at normal speed and will have the same output in number of sheet but some will be printed with a two color design formed by couples I and III and the others with a two color design formed by couples II and IV which obviously may be an entirely different design from the other. The action of the various couples in desired manner may be effected through suitable control of the throw-off means.

Referring to Figs. 2 and 3, in the present embodiment of the invention to permit control of the arms 27 I and 27 III independently of the arms 27 II and 27 IV, these arms may be provided with cam followers 31 disposed in different planes and in the present instance the followers for the arms 27 I and 27 III project forwardly viewing Fig. 1, and those on the arms 27 II and 27 IV project rearwardly. The cam mechanism for controlling the several arms may comprise two cam discs, an

outer disc 33 and an inner disc 35, having on their opposing faces cam tracks facing toward each other, the track of cam 33 receiving the followers for arms 27 I and 27 III controlling couples I and III and the track of cam 35 receiving the followers of arms 27 II and 27 IV controlling couples II and IV.

In Figs. 4^a and 4^b I have shown the form 10 of the cams utilized when the press works as a four color press. Referring to Figs. 1 and 4^a and considering arm 27 II and gripper bar 9, it will be seen that the gripper bar 9 is carrying a sheet of paper 15 through the couple II and that the follower of arm 27 II has just entered the inner or depressed portion of the cam track raising the impression cylinder of couple II into position to cause the plate cylinder to 20 print on the sheet. This portion of the cam track is suitably proportioned to the length of the sheet which is to be printed on and the follower then enters an outer or rise portion of the groove working the throw-off 25 and separating the form cylinder from the impression cylinder. As seen from Fig. 4^a, similar inner or depressed portions which serve to cause printing action of the couple are spaced from the one referred to a third 30 and two-thirds of the circumference respectively and as the gripper bars 11 and 13 are similarly spaced from the gripper bar 9 and the cam and ring gears rotate at the same angular speed, obviously the couple 35 II will be thrown in to print as the gripper bars 11 and 13 respectively reach the position occupied by gripper bar 9 in Fig. 1. The groove of cam 33 is a counterpart of the groove of cam 35 and is similarly 40 angularly positioned and as the angular relation of the several couples and the several arms 27 is fixed, the operation of the mechanism is such that each couple will print on each and every sheet. The operation of the cams 33 and 35 is similar to 45 the single cam shown in the patent referred to and there shown similar to cam 33 but two cams are utilized in the embodiment of the invention shown to provide for operating arms 27 having followers disposed in different planes to obviate changing the position of the cam followers when the press is adjusted to print two two-color jobs in the manner hereinafter described.

50 If it is desired to print two two-color jobs with the four couples, this may be effected by substituting suitable change cams for the cams 33 and 35 and in Fig. 5 suitable cams 33^a and 35^a are illustrated. Referring 55 to Fig. 5^a and Fig. 1, the arm 27 II is in an inner or depressed portion of the cam track and couple II is in position to print on the sheet carried by gripper bar 11. The succeeding outer or rise portion of the cam track, however, is relatively long and an-

other inner or depressed portion does not occur for about two-thirds of the circumference. Consequently the cylinders of couple II remain out of contact while the gripper bar 11 passes through the couple II in the position occupied by the gripper bar 9 in Fig. 1 and are not thrown in again to print until the gripper bar 13 comes to that position. The couple II and the couple IV, which is likewise controlled by cam 35^a, thus 60 print only on the sheets carried by grippers 9 and 13 and this printing may be in two colors, one for each couple. To prevent the couples I and III from printing on the sheets operated on by couples II and IV and to cause them to print on the remaining sheets, the arms 27 II and 27 IV are controlled by cam 33^a. This has a single 65 depressed portion disposed between the depressed portions of the track and cam 35^a, the angular position being such that it will 70 throw the couples in as the sheet carried by gripper 11 is brought to them. The outer or rise portion of the cam holds the couples out while the sheets carried by grippers 9 and 13 pass.

It will be obvious from this description that by a simple change in cams the press may be operated at the same speed measured in sheets per minute to produce either four 75 color work or two independent jobs of two color work. In the latter case when the cams, as shown in Figs. 5^a and 5^b, are utilized, each form operates at a rate measured in impressions per minute which is the sub- 80 multiple of the rate at which sheets are carried through the couples measured in sheets per minute.

In the form of the invention shown and utilizing the cams shown in Figs. 5^a and 5^b, 85 if one of the couples is permanently thrown out as by means of the device 37, the press can be utilized to print one two-color job and one single color job. By varying the number and form of the change cams, as 90 will be obvious, various other combinations may be effected and in the case of a two color press instead of a four color press, two single color jobs could be printed by substantially the same means as herein 95 shown.

In the form of press shown in Fig. 1 there are three grippers bars and when arranged with the cams shown in Figs. 5^a and 5^b couples II and IV print on the sheet 100 carried by gripper bars 9 and 13 and couples I and III on the sheet carried by gripper bar 11. Thus, two-thirds of the work is printed in one job and the remaining third in the other. In a press with four 105 gripper bars obviously the couples could be governed to print different jobs on alternate sheets by the use of cams rotating at the same angular speed as the ring gears like those herein shown. In the case of a 110

two color press where two gripper bars are ordinarily used half the sheets could be printed with one couple and half with the other.

5. By utilizing, for example, cam 35 of Fig. 4^a in combination with cam 33^a of Fig. 5^b, two-thirds of the sheets may be printed in four colors and every third sheet with two colors of the same design.

10. I have described in detail the particular application and mechanical embodiment of my invention shown as an example herein in connection with a particular form of press. Obviously the scope of the invention is not 15 limited to the particular arrangement and combination herein shown but the method may be practiced with various mechanisms and the invention find embodiment in widely varying forms.

20. What I claim as new and desire to secure by Letters Patent I shall express in the following claims:

1. Printing mechanism comprising means for carrying sheets along a cylindrical path, 25 form cylinders ranged about said path, cooperating throw-off means for the several forms comprising radially reciprocating levers, cam followers on the levers presented in different planes and a plurality of cams 30 cooperating with said followers.

2. Printing mechanism comprising means

for carrying sheets along a cylindrical path, form cylinders ranged about said path, cooperating throw-off means for the several forms comprising radially reciprocating 35 levers, cam followers on the levers presented in different planes and a plurality of cams cooperating with said followers, said cams having operating portions serving to cause printing from the corresponding forms, 40 which portions are disaligned on the several cams.

3. Printing mechanism comprising means for carrying sheets along a cylindrical path, form cylinders ranged around said path, 45 throw-off means comprising radial levers and a plurality of centrally arranged rotary cams each controlling one or more of said levers.

4. Printing mechanism comprising means 50 for carrying sheets along a cylindrical path, form cylinders ranged about said path, cooperating throw-off means for the several forms comprising radially reciprocating 55 levers, cam followers on the levers presented in different planes and a plurality of cams cooperating with said followers and means at will to render the motion of a given lever ineffective to operate the throw-off means.

In testimony whereof, I have signed my 60 name to this specification.

OTTO C. F. MEISEL.
